DENTAL APPARATUS

Harry Spiro, Chicago, Ill.

Application April 18, 1949, Serial No. 88,169

11 Claims. (Cl. 32—17)

1

This invention relates to dental apparatus and particularly to impression trays. In the making of dental prosthetics, such as bridges and partial plates, it is essential that a good impression be made. In many instances, poor impressions result from the apparatus now available and used in the art. Thus, conventional trays for holding impression forming materials all rely upon a large amount of excess impression-forming material for the success of the procedure.

It is essential to eliminate air bubbles at the surface to be copied. To this end it has been the practice to rely upon a large amount of excess impression-forming material. Thus, as the tray was forced into final position, surplus impression-forming material would be forced out from the edges of the tray. The surplus material, while performing a useful function, frequently made the patient uncomfortable to the point of gagging and thus rendered the making of a good impression difficult.

This invention provides a tray construction which makes it possible to improve the quality of an impression while reducing the amount of surplus material. It is thus possible to make an impression with far less inconvenience to the patient so that a good impression may be obtained the first time. In addition, the resulting impression obtained by the use of my invention is less likely to have flaws than is true with impressions made by conventional means.

My invention provides for maintaining the impression-forming material under some pressure at the impression surfaces, such as teeth and gingiva, and permits excess impression-forming material to flow under pressure along the impression surface and then free of the tray. Thus any air bubbles normally occurring at the necks of the teeth will be washed or blown away and the material itself will finally rest in intimate contact with the impression surface. This is obtained without the use of an excessive quantity of impression-forming material so that the final impression may be made with less discomfort.

In general, my invention provides, in addition to a conventional tray, an auxiliary member telescopically arranged with respect to the tray side so that in effect there is formed an extension of the tray side thus rendering the tray initially deeper than normal. In the use of my invention, the tray and its extension are filled with impression-forming material and inserted into the oral cavity for making an impression. Thereafter force is exerted upon the tray proper to telescope the extension inwardly toward the tray. Thus a

flow of impression-forming material along the tooth and gingival surfaces is generated. This flow of material is sufficient so that any air bubbles are removed. Due to the pressure on the impression material, the material will penetrate all crevices and nooks in the impression surface to provide a final impression which is true in all details.

The invention may be applied to any type of tray whether for use with maxillary or mandibular dentures or bridges and may be used with either plain or water-jacketed types of trays.

In order that the invention may be fully understood it will now be explained in connection with the drawings wherein Figure 1 is an isometric view of a tray embodying the present invention for use in taking a maxillary impression. Figure 2 is a detail of the hinge portion of the structure shown in Figure 1. Figure 3 is an isometric view generally similar to Figure 1 but showing a tray for use in taking a mandibular impression. Figure 4 is a detail of the hinge portion of the structure shown in Figure 3. Figure 5 is a side detail of the clamp portion of the structure shown in Figure 1. Figure 6 is an end view of the clamp portion of the structure shown in Figure 5. Figure 7 is a perspective detail of a tray embodying the present invention for use in making a partial denture or bridge. Figure 8 shows a modification.

Referring first to Figures 1 and 2, the tray comprises ridge portion 10 having vault portion 11 and flange portion 12. It will be noted that flange portion 12 varies from a minimum height at the heel of the tray to a maximum at labial portion 13 of the tray as seen in Figures 5 and 6. The tray has handle 15 rigidly attached to the bottom thereof below labial portion 13. This structure is conventional.

Hingedly secured at 17 and 18 is extension 20 consisting of a curved portion extending around on the inside surface of the flange of the tray. Portion 20 may extend on the outside if desired. Portion 20 is preferably provided with a large number of apertures, the size and spacing being varied to suit requirements. Instead of perforations, roughening of the inside surface may be provided. This is to provide for mechanical gripping of the compound. Extension 20 may be turned on its hinges or pins to swing up from the labial portion of the tray. In the normal use of the tray, portion 20 need not extend very far up from the tray edge and its maximum outer position for normal use may be as shown in Figures 5 and 6. For cleaning purposes and for

initially filling the tray with impression-forming material, it may be advisable to swing portion 20 clear of the tray.

It is desirable to provide means for retaining portion 20 in a predetermined open position as shown in Figures 5 and 6. To this end, tray flange 13 may carry clip 23 to which portion 25 is attached.

Portion 25 has spring tongue 26 which has locking portion 27 cooperating with indentation 28 in the tray flange for temporarily locking portion 20 in its upper position. Handle 30 for the locking clip is provided for releasing the lock and for exerting the necessary force upon portion 20 relative to tray 10 so that the two may be moved predetermined to a closed position. Thus a gauge or measuring action may be provided.

Referring now to Figures 3 and 4, the same general structure is shown with the exception that ridge 10' of the tray is bounded by lingual flange portions 11' leaving an open space for clearing tongue tissue. In this construction, shown in Figures 3 and 4, portion 20' is hinged-secured by pin 17' and 18'. It is understood, however, that the same general hinge structure shown in Figure 1 may be used in Figures 3 and 4. In the construction shown in Figures 3 and 4, portion 20' has portion 21' extending over the hinge or pin and joined to portion 22' forming the up-standing inside boundary of the hinge portion.

In the modification shown in Figures 3 and 4, the same clip structure may be used as shown in Figure 1. Again it may be desirable to swing portion 20' clear of the tray when initially filling the same. In this modification it will be noted that portion 20' forms an extension for the tray side at both the inner and outer parts of the tray.

Referring now to Figure 7 there is shown a construction which may be used in connection with making an impression for a bridge. This construction comprises tray 35 which may be of the water-jacketed type, having water inlet and outlet pipes 36 and 37 respectively, these pipes also serving as a handle for the tray. Extension portions 40 and 41 are joined by cross-piece 42. The entire extension is pivotally secured by cross-piece 42 secured to pin 43 carried by the tray flanges. The extension has handle 45 in proximity to pipes 36 and 37. The tray proper has bottom portion 47 apertured at 48 for accommodating tongue 50 carried by extension 40. Tongue 50 has bumps 51 and 52 cooperating with the side of slot 48 to provide a lock in generally the same manner that the clips function in Figures 5 and 6.

The construction shown in Figure 7 may be opened so that the perforated extension is clear of the tray proper to promote filling of the tray with impression-forming material. In the use of a tray such as shown in Figure 7, it may be found desirable to provide dams at the two tray ends and along the edges for preventing flow of impression-forming material at the ends. These dams may be formed of temporary impressions of the teeth or gums against which these may normally rest. Such dams may be made of materials now in use in dental offices and, when disposed at the two ends of the tray, will provide sufficient sealing action so that proper operation may result.

In the use of a structure embodying the present invention, the tray proper will be filled with impression-forming material in the conventional manner. The extension in Figure 1, for example,

will then be in its upper position. The tray is thereupon inserted into the oral cavity and disposed firmly in position against the surfaces to be impressed. Thereupon the dentist or technician will begin to push handle 15 and the tray against handle 30 so that the extension and tray proper are slowly forced into a closed position while the entire tray is maintained tightly in position against the impression-forming surface. Due to the back pressure created by side 20, impression-forming material will be pressed against the desired surface. While some impression-forming material may ooze out through the perforations, most impression-forming material will escape over the free sides and edges of the entire tray structure as usual. By proper filling of the tray with impression-forming material and proper manipulation of the two portions of the tray with respect to each other, it is possible for an operator to obtain a desired impression without the use of an excessive quantity of the impression-forming material.

It is possible to have the tray flange on the inside of the extension when closed and such a construction is shown in Figure 8. Thus referring to Figure 8, tray proper 55 has auxiliary member 56 pivoted at 57. The view only shows a detail of this, it being understood that the remainder is similarly provided with a pivoted portion in a manner generally similar to Figures 1 and 3 as far as those trays are concerned. It is understood, of course, that the same construction of the auxiliary member outside the tray proper may be applied to the construction shown in Figure 7. In Figure 8, the auxiliary member is shown as having small spines or roughenings 60 on the inside surface of the auxiliary member for anchoring the compound to the auxiliary member material.

The construction of the tray shown in Figure 1 may be modified, if desired, by having the rear portion thereof extend straight across from heel to heel with pivot means disposed along this continuous portion.

A substantial advantage accruing from the use of the present invention, will become manifest in connection with the manufacture of plaster of Paris casts from the impression. As is well known, an impression of compound in a tray is first formed and thereafter a plaster of Paris cast of this impression must be made. After the plaster of Paris has set, it is necessary to separate the plaster of Paris cast from the compound and tray. Due to the reinforcing action of the tray walls, the compound does not yield very much when an attempt is made to pull the plaster of Paris cast away. In such an operation, it may occur that projecting portions of the cast, corresponding to ill-formed teeth in the patient's mouth, will be strained and broken. By virtue of the present invention, it is simple to swing the auxiliary member and cast away from the tray proper. Hence the cast may be readily removed from the auxiliary member.

What is claimed is:

1. A dental tray assembly comprising a tray proper shaped to hold impression-forming compound for oral prosthetic work, said tray proper having ridge and flange portions, and an auxiliary member having the same general shape as the flange proper but having substantially no ridge portion, said auxiliary member being dimensioned to telescope said flange and being adapted to be forced into telescoping relation with the tray proper during the taking of an impression

5

whereby the impression-forming compound is subject to pressure generated during the telescoping action and flows along the impression surface.

2. The structure according to claim 1 wherein said auxiliary member is pivotally secured to the tray proper.

3. A dental tray assembly comprising a tray proper shaped to hold impression-forming compound for oral prosthetic work, said tray proper having ridge and flange portions and an auxiliary member having the same general shape as the flange of the tray proper but not having any substantial ridge portion, said auxiliary member being dimensioned to telescope within the tray proper along the flange portion, said auxiliary member being forced into telescoping relation with the tray proper during the taking of an impression with the impression-forming compound flowing under pressure along the impression surface.

4. The structure according to claim 3 wherein said auxiliary member is pivotally secured at the rear or heel portion of the tray proper.

5. A dental tray assembly comprising a tray proper shaped to hold impression-forming compound for oral prosthetic work, said tray proper having ridge and flange portions, said tray proper having heel and labial portions with a handle extending from the labial portion of the tray proper, an auxiliary member having the same general shape as the flange portion of the tray proper but having substantially no ridge portion and being dimensioned to telescope said flange portion, means for pivotally securing said auxiliary member and tray proper at the heel portion of the tray proper so that the auxiliary member may move in or out of the labial portion of the tray proper and means carried by the labial portion of said auxiliary member and cooperating

6

with the labial portion of the tray proper for determining the limit of telescoping action of the auxiliary member into said tray proper.

5 6. The structure according to claim 5 wherein said auxiliary member is smaller than the tray proper and is adapted to fit within the flange portion of the tray proper.

10 7. The structure according to claim 5 wherein locking means are provided for maintaining the auxiliary member and tray proper in a predetermined open position for initiating impression taking.

15 8. The structure according to claim 5 wherein said tray proper has a vault portion.

9. The structure according to claim 5 wherein said tray proper has a lingual flange portion and wherein said auxiliary member has a corresponding lingual flange portion.

10 10. The structure according to claim 5 wherein 20 said tray proper is of the type for use with bridges and wherein the auxiliary member and tray proper have labial and lingual flanges.

11. The structure according to claim 5 wherein 25 one movable part carries a spring clip and the other movable part has means cooperating with spring clip for limiting the movement of the two members with respect to each other.
